UNITED STATES PATENT OFFICE.

HUBERT F. KRANTZ, OF BROOKLYN, NEW YORK.

SELF-ACTUATING SAFETY-PANEL.

1,248,431.

Specification of Letters Patent. Patented Nov. 27, 1917.

Application filed February 18, 1916. Serial No. 79,094.

To all whom it may concern:

Be it known that I, HUBERT F. KRANTZ, a citizen of the United States, and residing at Brooklyn, in the county of Kings and State 5 of New York, have invented a new and Improved Self-Actuating Safety-Panel, of which the following specification is a full disclosure.

This invention deals with certain improvements in safety panel boxes designed 10 to afford more convenient access for purposes of inspection and replacement of safety fuses and it embodies certain of the broader features claimed in my co-pending 15 case No. 42,956; adding thereto certain further provisions in the construction of safety panel boxes.

Among other objects, this invention proposes an arrangement such that the door 20 cannot be either opened or closed save when the switch blade is in open circuit position, and such that an attempt to either open or close the door will throw the blade in set position.

Another object is to provide a simple arrangement whereby the fuse plugs will not 25 only be very easily replaced but so that the opening of the door will shift the make-and-break mechanism into fully exposed view.

Other objects will be in part obvious from the annexed drawings and in part indicated in connection therewith by the following analysis of this invention.

This invention accordingly consists in the 35 features of construction, combinations of parts, and in the unique relations of the members and in the relative proportioning and disposition thereof; all as more completely outlined herein.

To enable others skilled in the art so fully 40 to comprehend the underlying features thereof that they may embody the same by the numerous modifications in structure and 45 relation contemplated by this invention, drawings depicting a preferred form have been annexed as a part of this disclosure, and in such drawings, like characters of reference denote corresponding parts throughout 50 all the views of which:—

Figure 1 represents the invention in longitudinal cross-section with the switch blade in closed circuit and Fig. 2 shows the same with the blade in open circuit. Fig. 3 is a 55 plan of this apparatus and Figs. 4 and 5 are

details showing the operation of the door lock.

Referring to the drawings, A designates generally a structure in the nature of a box or other suitable enclosure which may be 60 constructed in various ways, as for example, by means of sheet metal sides and ends 1 and 2 connected, if desired, with a similar floor member 3, and interiorly providing a base-plate 4 of insulating material which is 65 utilized as a mounting for one or more terminal elements. As here shown, associated with this base-plate is a partition 5 of insulating material which divides the interior of the box into a gutter or channel B carrying 70 the leading-in wires from the main supply and containing the terminals 6 thereof which, by means of suitable screws 7, are connected directly to main-line bus bar or switch terminal 8 having a Z-shape and extending upwardly along the gutter side of the partition 5 and protruding over the same and terminating in a contact portion 9 against which the switch blade may directly bear. An insulating strip 10 surrounds these various main-line terminals and intervenes between the same and the fixed or stationary portion 11 of the cover of the box. It is to be understood that this portion 11 need only be removed in rare instances, as in case of anything happening to the leading-in wires within the gutter B, and it is, therefore, normally closed.

The remaining space of the safety panel box is occupied by the make-and-break 90 mechanism and also the safety fuse terminals, and the current carrying parts are normally inclosed or protected against whenever they are "live", by means of one or more doors C serving as an obstructing element to prevent the hand of the user from touching any "live" parts. This door, however, is so arranged, as for instance by means of the hinge or its equivalent 12, that it may be displaced or shifted out of its 100 normal position to permit access, especially for the purpose of replacing fuse units, and preferably also to afford inspection of the switch blades and their operating mechanisms. In the illustrated embodiment of 105 this invention this is very conveniently provided for by mounting a part of the make-and-break mechanism on the shiftable door C so that when the door has been opened, the make-and-break mechanism will be 110

brought into a very accessible inspecting position. Now, the general arrangement is such that whenever the door has been displaced, and access is thereby afforded to the 5 fuse units, the fuse plug terminals will all become "dead". Likewise, under the same conditions, this embodiment causes the make-and-break elements to become dead, as by swinging the switch blade into its open 10 circuit position. The particular mechanism here resorted to for disclosing this mode of operation is constructed as follows:

Mounted on the base board 4 are two terminals 13 and 14 which are adapted to act 15 as spring clips to permit a ready substitution of any suitable fuse plug. These terminals 13 and 14 are merely typical of any variety of socket or arrangement adapted separably to receive fuse units. The one 20 terminal is connected with a branch line circuit by means of a part 15, and the other terminal 13 is connected preferably directly with a contact piece 16 which receives the current from a suitable switch blade when 25 in contact therewith. Preferably this contact 16 is complementary to the contact 9 and is arranged opposite the same diagonally across the axis of rotation of a suitable switch blade S. This switch blade is 30 mounted to rock about the axis v, and is actuated by grasping the handle 69 and thereby swinging the arm O about its axis x, and thus, by means of the toggle mechanism, illustrated in detail in my copending 35 application No. 42,956, causing the switch blade S to be forced into and locked in its "closed circuit" position against the contacts 9 and 16, or permitted to snap into "open circuit" position by spring action.

40 This mechanism, being closely detailed in said co-pending case, need not here be specifically described as in this connection it is employed to typify any desired type of switch mechanism adapted to be mounted 45 upon the shiftable door C.

A door-locking handle D is in this embodiment preferably arranged so as to be bodily movable with the door itself so that it may be used not only for unlocking the 50 door but also for bodily displacing the door during its own shift in space, although it may be arranged so as to perform the former function alone by providing the door with a separate handle to be used for shifting the door after it has been unlocked by 55 actuation of the other. Here the handle D turns about a pivoted shaft 17 to which is affixed a rotatable plate 18 on the inner side of the door C. Extending from this plate 60 18 is a locking latch 19 which is adapted to catch underneath a lip 20 secured to a stationary part of the box and thereby prevent the door from being opened when the handle is in the position shown by Fig. 1. 65 The construction is also such that the door

cannot be closed when the handle is in said position, and this is accomplished by means of a second projection E which is arranged so that it will impact the upper surface of the lip 20 should an attempt be made to 70 close the door when the handle is in the wrong position.

Now this invention furthermore proposes a connection between this handle and the switch mechanism such that the door can 75 neither be opened nor closed save when the switch is in open circuit position; and furthermore such that an operation of the handle into this door opening position will result in a shifting of the switch blade into its 80 open circuit position.

The switch mechanism presents in addition to the actuating lever O a second actuating member T which is effective to cause the switch blade to move into its open circuit position; in this instance by breaking the toggle in the same way that the corresponding member T can be pushed to break the toggle in the switch mechanism shown in my said co-pending case. This member 85 T provides a slot 21 whereby the pin u guides it, and its one end bears against or is pivoted to either the arm O or the arm R or the toggle link swinging about the shaft x so that, if the part T be pushed to 90 the left, it will cause the switch S to swing into its open circuit position. Likewise, the connection is such that if the arm O be swung into the position shown by Fig. 1 of necessity the part T will then be protruded 100 toward the right as shown by Fig. 1, in which case the switch S establishes electrical connection.

An interponent F intervenes between the part T, or the rail 22 connecting a plurality 105 of similar parts T and the handle D in such a manner that when the handle is in the position shown by Fig. 2 (permitting the door to open) the part T must of necessity be in its "open circuit" position; and conversely, 110 when the part T is in its "closed circuit" position, interponent F compels the handle D to assume the position shown by Fig. 1, thereby preventing the door from being opened, if it be closed; or from being closed 115 if it be open. This effect is conveniently attained by pivoting the interponent F to the part 18 by means of the pivot 23 and by causing its other end to be guided by a part 24 into proper relation with the cross rail 22. 120

It should be pointed out that the handle D, with the parts directly connected to be operated thereby, constitutes an auxiliary manual control means for the switch blade in that said parts are capable, independently of the main operating or control arm O, of controlling movement of the switch blade from one of its positions to another at certain times. The effectiveness of this auxiliary control means is dependent upon the 130

position both of the movable door and of the main control means for the reason that the switch blade can never be in the "on" position except when the handle is thrown 5 to a corresponding position, and it even then is never in engagement with the opposite contact terminals except when the door is closed. Thus the position of the door, which constitutes a part of the protecting 10 casing for the switch blade, determines the effectiveness of the auxiliary control means.

As many changes could be made of this construction without departing from the scope of the following claims, it is intended 15 that all matter contained in the above description, or shown in the accompanying drawings, shall be interpreted as illustrative only and not in a limiting sense.

Having thus revealed this invention, I 20 claim as new and desire to secure the following combinations of elements, or equivalents thereof, by Letters Patent of the United States:

1. A switch mechanism combining a casing 25 having an opening thereinto, a switch blade, manual control means for the switch blade, a displaceable closure member for said opening, a manually operable lock operable independently of the manual control 30 means for the switch blade for preventing displacement of said closure member, and means for causing said switch blade to assume open circuit position as said lock is manually moved into unlocking position.

35 2. A switch mechanism combining a casing having an opening thereinto, a switch blade, manual control means for the switch blade, a displaceable closure member for said opening, a manually operable lock operable independently of the manual control 40 means for the switch blade for preventing displacement of said closure member, and connections between said switch blade control means and said lock for moving said 45 lock into locking position when said switch blade is thrown into closed circuit position.

3. A switch mechanism combining a casing 50 having an opening thereinto, a switch blade, manual control means for the switch blade, a displaceable closure member for said opening, an element operable to displace the closure member, a part movable by said element to lock the closure member against displacement, and connections between 55 said part and said switch blade whereby to constitute an auxiliary control means for the switch blade.

4. A switch mechanism combining a casing 60 having an opening thereinto, a switch blade, manual control means for the switch blade, a displaceable closure member for said opening, a handle mounted on said closure member having a part to lock said closure member, said handle being adapted to 65 be actuated first to unlock the closure mem-

ber and then to displace it, and means whereby the handle constitutes part of an auxiliary control means for the switch blade operable to cause the switch blade to assume an open circuit position when said closure 70 member has been unlocked.

5. A switch mechanism combining a casing 75 having an opening thereinto, a switch blade, manual control means for the switch blade, a displaceable closure member for said opening, a manually operable lock operable independently of the manual control 80 means for the switch blade for preventing displacement of said closure member, and means whereby said lock constitutes an auxiliary manual control means for the switch blade.

6. A switch mechanism combining a casing 85 having an opening thereinto, a switch blade, manual control means for the switch blade, a displaceable closure member for said opening, means independent of said switch blade control means effective to prevent closure of the closure member when said switch blade is in closed circuit position, and said last means comprising an auxiliary manual control medium for the switch blade.

7. A switch mechanism combining a casing 90 having an opening thereinto, a switch blade, manual control means for the switch blade, a displaceable closure member for said opening, means independent of the switch blade control means for preventing said closure member from being opened when said 95 blade is in closed circuit position, and said last means comprising an auxiliary manual control medium for the switch blade.

8. A switch mechanism combining a casing 100 having an opening thereinto, a door displaceable to open and close said opening, a switch blade connected to be shifted bodily into functioning position by closing said door, manual control means for the switch blade, and means independent of said switch blade control means for preventing said door 105 from being closed when said switch blade is in closed circuit position.

9. A switch mechanism combining a casing 110 having an opening thereinto, a door displaceable to open and close said opening, a switch blade connected to be shifted into functioning position by closing said door, manual control means for the switch blade, and means independent of said switch blade 115 control means for causing said switch blade to assume its open circuit position whenever said door is either opened or closed.

10. A switch mechanism combining a casing 120 having an opening thereinto, a switch blade, manual control means for the switch blade, a displaceable closure member for said opening, auxiliary control means for the switch blade, and means whereby the effectiveness 125 of the auxiliary control means is de- 130

41
terminated by the position of the closure member.

11. A switch mechanism comprising a movable contact part, control means therefor, auxiliary control means for said movable contact part, a protecting member for the switch mechanism, said protecting member having a movable part, and means whereby the effectiveness of the auxiliary control means is determined by the position of the movable part of the protecting member.

12. A switch mechanism having a movable blade, an operating handle for moving said blade, a protecting member for protecting said blade, said protecting member having a displaceable part displaceable to give access to said blade, auxiliary control means for the blade, and means whereby the effectiveness of said auxiliary control means is determined by the position of said displaceable part.

13. A switch mechanism combining a casing having an opening thereinto, a door for the opening pivotally mounted to swing into and out of closing position, a switch mechanism carried by the door to swing therewith and comprising a double-ended switch blade pivoted intermediate its length to swing its opposite ends into and out of functioning position, and a pair of contacts for the respective ends of the switch blades arranged with respect to the door hinge so that when the door is swung open the ends of the switch blade will move in opposite directions away from their respective contacts.

14. A switch mechanism combining a casing having an opening thereinto, a door for the opening hinged to swing into and out of closing position, a contact member arranged within the casing, a switch mechanism carried by the door to swing therewith, a barrier arranged within the casing between said contact member and said opening to render the contact member practically inaccessible from said opening when the door is open, and the switch mechanism comprising a contact part which swings about said barrier into and out of position for functioning with said contact member when the door is closed or opened.

15. A switch mechanism comprising a cas-

ing having an opening thereinto, a closure part for said opening, said casing providing a compartment having an overhanging cover 55 ledge adjacent the opening, a contact member terminating at the under face of said ledge, a switch device for co-operating with said contact member, and a barrier arranged within the compartment between said contact member and said opening to render said contact member practically inaccessible from said opening when said closure part is removed.

16. A switch mechanism combining a casing having an opening thereinto, a displaceable closure member for the opening, a latch for the closure member adjacent one edge thereof, a switch mechanism adjacent the opposite edge of the closure member, and connections extending from the latch across the closure member to the switch mechanism operative to cause the switch mechanism to assume open circuit position when the latch is operated to release the closure member. 65

17. A switch mechanism combining a casing having an opening thereinto, a closure member for the opening movable into and out of closing position, a latch for retaining the closure member closed, a switch device movable into "on" and "off" positions, the latch comprising a handle part and a locking plate rotatable by the handle part into and out of locking position, a member connected with the locking plate and extending 80 therefrom into operative relation with the switch device adapted to insure an off position of the switch device when the locking plate is in unlocking position, and an extension formed upon the locking plate operable 85 when the closure member is being closed to constitute a stop for engaging against an opposing surface portion of the casing to prevent movement of the closure member into near closing position except when the locking plate is in unlocking position. 90

In witness whereof, I hereunto subscribe my name, as attested by the two subscribing witnesses.

HUBERT F. KRANTZ
